UNITED STATES PATENT OFFICE.

FRANK NICHOLS, OF MONROE, NEW YORK.

HULL FOR MARINE CRAFT

1,116,724.

Specification of Letters Patent. Patented Nov. 10, 1914.

Application filed August 25, 1913. Serial No. 786,464.

To all whom it may concern:

Be it known that I, FRANK NICHOLS, a citizen of the United States, residing at Monroe, in the county of Orange and State of New York, have invented a new and useful Improvement in Hulls for Marine Craft; and I do hereby declare the following, when taken in connection with the accompanying drawings and the characters of reference marked thereon, to be a full, clear, and exact description of the same, and which said drawings constitute part of this application.

Figure 1 is a view in side-elevation of a hull embodying my invention. Fig. 2 is a vertical longitudinal section thereof. Fig. 3 is a view partly in front elevation and partly in transverse section thereof. Fig. 4 is a similar view of a modified form. Fig. 5 is a view in side-elevation illustrating the combination of my improved construction in a non-angular hull. Fig. 6 is a diagrammatic body-plan thereof. Fig. 7 is a view partly in front elevation and partly in transverse section of another form which my invention may assume.

This invention relates to an improvement in hulls for marine craft, and particularly to that class of surface hulls which are transversely built up of sections of straight ribs set at an angle to each other and joined together by longitudinal chine or knuckle pieces. This type of hull is commonly known as V bottom (usually two sections each side of the keel) or dory hulls; (two or more sections on either side of the keel) but which for convenience I will hereinafter term angular hulls.

The object of this invention is to produce a hull of relatively low cost which at the same time shall be of pleasing lines and combine the most desirable features of the various types of hulls at present in use.

With the fact in mind that a curved or rounded surface minimizes suctional-drag and produces better sea riding qualities than a flat surface, a further object of this invention is to replace the flat sections at present employed in the construction of angular hulls with sections whose transverse form will be substantially that of an arc or segment of a circle.

With these ends in view my invention consists in the construction hereinafter described and particularly recited in the claims.

My invention can best be set forth by first outlining the present state of the art of hull construction as typified by angular and non-angular hulls. I might state in this connection that by the use of the words non-angular hulls I refer to the hulls common to practically all large marine carriers and predominant in smaller pleasure craft, which are not built up of sections but employ various irregular curves to obtain their form. Non-angular hull construction is the most versatile construction at present in use. It is adapted to practically all the requirements of the art by virtue of the unlimited forms into which its one-piece ribs may be molded; but for reasons that will hereinafter appear it is far the most costly. In non-angular hulls as in other types of hulls each succeeding rib must be formed as near like its predecessor in general form as is practical, in order that the longitudinal strakes of planking will strike each and every rib fairly. In other words there must be no abrupt changes in transverse form but only a gradual transition from one form to another. It will readily be seen that if the convex portion of one rib were to have the same transverse position as the concave portion of an adjacent rib, undesirable bulgings and depressions would result.

The mere employment of ribs of the same form would not necessarily result in the self-fairing feature which is a salient feature of my invention unless the concave and convex portions of each rib stood in the same relative position as the similar portions of the adjacent ribs. The keel and deck-plates as well as the chine-pieces, if any are employed, will converge to a greater or less extent and the ribs, if they are of irregular form—even though each rib be identical, will have to be shortened at both ends in order to maintain their various curves in the same relative position as the corresponding curves of the adjacent ribs.

The bend of ribs (steel ribs in particular) of irregular form such as are employed in non-angular hulls, is an exceedingly difficult and laborious task. It necessitates the services of expert craftsmen who specialize in this line of work, to insure the correct reproduction and enlarging of the intricate curves laid down by the designer, as it is seldom if ever that any two consecutive ribs are alike in form.

Angular hulls were evolved primarily to

simplify and consequently reduce the cost of hull construction by obviating the necessity of fairing each rib. In this method of construction the hull is made up of a series of flat sections set at an angle to each other and joined together as a rule by longitudinal chine pieces. These chine or knuckle pieces constitute the mold of fairing points of the hull; and when they are properly positioned with relation to the keel the straight ribs introduced between them and also between the keel and the two innermost chine pieces cannot present other than a fair and even surface for the application of the planking or such other covering as may be employed. This "self-fairing" feature, for which the angular hull is notable, reduces the figuring required, both in designing and building a hull to a minimum.

Notwithstanding its low cost and simplicity, the angular hull has serious drawbacks for which the flat surfaces of its hull sections are mainly responsible. These flat surfaces, for obvious reasons, disqualify it, to a great degree, for sea-going service.

Heretofore the only known method of obtaining the self-fairing feature in angular hulls has been by employing straight ribs; which are objectionable because of the resultant flat surfaces. It will be understood that ribs of substantially the same form must be employed if the self-fairing feature is to be obtained. The self-fairing feature is accomplished, in my improved hull by the employment of circular-arc ribs as in contrast to the straight ribs of the present angular hull.

In carrying out my invention as shown in Figs. 1, 2 and 3, I employ a keel 2 of ordinary construction upon which is mounted the stem 3 and the transom 4. On either side of the keel 2 is a chine or knuckle piece 5 and a deck plate 6 extending fore and aft between the stem 3 and the transom 4. These chine pieces and deck-plates are so placed as to form, in conjunction with the keel, the mold or fairing points of the hull while it is under process of construction. Extending between the keel 2 and chine pieces 5 and also between the chine pieces and the deck-plate 6, at substantially right angles, are circular-arc ribs 7. Suitable planking 8 is applied to the ribs 7 to form circular-arc sections 9-9 and 10-10 on either side of the keel 2. Preferably the chine pieces 5 are suitably rabbeted as at 11 to receive the planking 8. It will be noted that the chine pieces are twisted in order to properly receive the ribs; which ribs, as shown in the particular form of hull chosen to illustrate my invention, are of a necessity varied in their degree of inclination. If it is desired to omit twisting the chines the ribs might be beveled to accommodate themselves to the said chines

and then, after the planking has been applied, the chines would be planed off to perfect the symmetry of the hull.

If desired, and as shown in Fig. 4, I may impose straight sections 12-12 upon the sections 9-9; or I may interpose concave circular-arc sections 13-13 between the sections 10-10 and the keel 2 as shown in Fig. 7.

When it is desired to incorporate my improved construction in non-angular hulls as clearly shown in Figs. 5 and 6, the midship portion may be built up of circular-arc sections 14-14 and 15-15, which merge at about the points x-x and z-z respectively into the bow or fore portion 16 and the stern or after portion 17; the said bow and stern portions being of non-angular construction. It is obvious that two or more circular-arc hull sections of different curvature might occupy the same horizontal plane and be merged into or reconciled to each other by ribs of any proper form.

It will be noted (Fig. 5) that the chine pieces 5 pass inside of the bow portion at the point x-x and inside of the stern portion at the point z-z; from which points respectively they extend fore and aft and supplant the bilge-stringers which would ordinarily be employed as longitudinal reinforcements in non-angular hulls. While the feature of utilizing the chine pieces to perform the function of bilge-stringers may be desirable, it is by no means a necessary feature.

In place of the chine pieces 5 I may elect to use short knee-like coupling pieces 18 to unite the various hull sections, as clearly shown in Fig. 4 of the drawings.

It is to be further noted that each of the individual circular-arc ribs comprising (a circular-arc hull-section (a group of circular-arc ribs) are, to all intents and purposes, of the same radii; although ribs of slightly different radii might be used. As an example: the sides of the midship portion of a large ocean-going vessel might, under my invention, be built of ribs of an 80 foot radius among which one or more ribs of a 5 foot smaller or larger radius might pass unnoticed as far as any difference in curvature was concerned; although this is undesirable and effects no greater economy.

In setting up a hull or portion of a hull embodying my invention various and varied methods may be employed; this being a matter of preference tempered, to a degree, by the type of hull and the materials used in its construction. Ordinarily the keel will form the base from which the hull will be constructed. After laying the keel the stem-piece and transom will be mounted thereon and rigidly braced in place after which the deck-plates and chine-pieces will be put in place in their carefully predetermined positions with respect to the keel and properly se-

cured to the stem-piece and transom; it being necessary at this time to give the chines the proper twist, if any is required, so as to accommodate them to the varying transverse

by the objects in view with particular regard to the services for which it is intended; whether for sea, river, passenger or freight service.

65

5 form of the hull.

The timbers, or other materials employed, having been previously molded or otherwise shaped into circular or semi-circular form of the proper radius, will be divided into segments of the necessary length and introduced as ribs between the keel and the innermost chine-pieces on either side thereof; between the various chine-pieces if more than one is employed on either side of the keel, and 10 also between the deck-plates and their adjacent chines. When the skeleton of the hull is complete, planking or other suitable covering is applied in any approved manner.

In setting up a hull embodying my invention, as just described, practically all the figuring required is employed while positioning the chines and deck-plates in their predetermined positions with relation to the keel. The construction is also accomplished 20 without the aid and attendant expense of the elaborate and cumbersome false-work necessary in the construction of other than angular hulls.

Circular-arc ribs may be formed end to end in a continuous piece as previously described and as they have but one form throughout their entire length (either convex or concave—never both) it makes no difference whatever which end is cut off, to 30 make them fit in place. The task of applying circular-arc ribs to a hull is no more difficult than fitting rafters in a building.

My improved construction is also advantageous in so far as the problem of determining 40 the cross-sectional area of a hull at any given point is rendered comparatively simple; a matter of no small importance in designing.

While I have shown the invention as applied to wooden hulls, it is apparent without further illustration, that it is equally applicable to steel hulls.

The main feature from which most of the advantages of my improved construction 50 emanate, is the combination of the curved surfaces of the non-angular hull with the self-fairing feature of the angular hull; a combination heretofore unknown.

I wish to have it understood that I do not 55 limit my invention to any detail of construction, such as the number or position of the sections which may be employed; nor do I limit myself as to the various other types of hulls with which it may be combined. The number, position, and radii of 60 the circular-arc sections will be determined

I claim:—

1. A hull for marine surface craft having hull-sections set at an angle to each other, an equal number of said hull-sections on either side of the longitudinal center of said 70 hull formed transversely as segments of circles.

2. A hull for marine surface craft having a keel and hull-sections set at an angle to each other, an equal number of said hull-sections on either side of said keel formed 75 transversely as segments of circles.

3. A hull for marine surface craft having a keel and hull-sections set at an angle to each other, an equal number of said hull-sections on either side of said keel formed 80 transversely as segments of circles; said circular-arc sections abutting at either or both ends against portions of the hull formed of other than circular-arc ribs.

4. A hull for marine surface craft having a keel and hull-sections set at an angle to each other, an equal number of said hull-sections on either side of said keel formed 85 transversely as circular-arc segments, said circular-arc hull-sections gradually changing their angle of inclination with respect to the keel and to their own mid-portions as they approach the bow and stern portions of the hull.

5. In a hull for marine surface craft having hull-sections set at an angle to each other, the combination with the keel, chine-pieces and deck-plates thereof, of circular-arc ribs extending between said chine-pieces 90 and keel, and also between said chine-pieces and deck-plates at substantially right-angles thereto.

6. In a hull for marine surface craft having hull-sections set at an angle to each other, the combination with the keel and deck-plates thereof, of a series of chine-pieces arranged between said keel and deck-plates substantially parallel therewith, and circular-arc ribs extending transversely between said series of chine-pieces and the keel, 105 between said series of chine-pieces and the deck-plates, and also between the various individual chine-pieces of said series.

In testimony whereof, I have signed this 110 specification in the presence of two subscribing witnesses.

FRANK NICHOLS.
